UNITED STATES PATENT OFFICE

2,036,812

REFRIGERATING MACHINE

Ralph E. King, Fort Wayne, Ind., assignor to General Electric Company, a corporation of New York.

Application October 11, 1934, Serial No. 747,879

3 Claims. (Cl. 62—116)

My invention relates to refrigerating apparatus and more particularly to refrigerating apparatus adapted for household or domestic use.

In household refrigerators it is common practice to provide a cabinet having a cooling compartment and a machinery compartment. A compressor, a motor for driving the same and a condenser are usually located in the machinery compartment, a fan being provided to circulate air therethrough. The cooling air which is circulated through the machinery compartment by the fan often contains dirt and other foreign matter which collects on the machinery contained in the machinery compartment and particularly on the heat radiating surfaces of the condenser. The collection of dirt is not only unsanitary, but if it is allowed to accumulate on the surfaces of the condenser member, it will very materially decrease its efficiency, as it reduces the air flow through the condenser and acts as a heat insulator on the heat dissipating fins.

It is an object of my invention to provide a novel arrangement of parts in a refrigerator of the type described in which the cooling air is circulated through the machinery compartment so as to utilize the same most effectively for cooling the condenser and other portions of the machinery therein, and in which the surface of the condenser is easily accessible for cleaning purposes.

It is a further object of my invention to provide a refrigerator of the type described in which the air inlet of the machinery compartment is located near the floor and in the base of the machinery compartment, and in which dirt and other foreign matter is prevented from entering the space beneath the refrigerator cabinet.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawing in which the single figure is a side view, partly in section, of a domestic refrigerator embodying my invention.

Referring to the drawing, I have shown a refrigerator comprising a cooling chamber or food compartment 10 which is cooled by a suitable cooling unit 11, the latter being supplied with refrigerant from the apparatus contained

in a machinery compartment 12. In the form of my invention shown in the drawing, the machinery compartment 12 is located below the cooling compartment 10 and contains a compressor unit 14 which is driven by an electric motor 15 through a suitable belt connection 16. An air cooled condenser 17 having a plurality of vertical closely spaced fins 17a, is mounted near the front of the machinery compartment 12. A fan 18 is located in the machinery compartment for circulating cooling air therethrough and is driven directly by the electric motor 15. An air inlet 19 is provided for the machinery compartment 12 preferably in the forward portion of a base 20 on which the cabinet is supported. This base includes a rectangular frame 20a and legs 20b made of angle iron, and a mop-board 21 completely surrounding the frame of the base which is welded to the angle iron frame and the legs. This mop-board is provided with an offset portion, or recess, 22 in the front thereof, which provides a convenient toe space for persons who are standing in front of the refrigerator. Since the mop board 21 surrounds the entrance to the air inlet 19 on three sides, it effectively prevents dirt or other material from the floor surface entering the space under the refrigerator cabinet which might otherwise be carried there by the movement of the cooling air across the floor or when the floor is mopped or dusted. A removable panel 23 is provided for closing the front of the machinery compartment 12. Easy access may be had to the face of the condenser 17 through the front of the compartment 12 upon removal of panel 23.

In the operation of the refrigeration apparatus illustrated in the drawing, refrigerant is compressed in the compressor 14 and passes through conduit 24 to the condenser 17, where the refrigerant is condensed into a liquid and then collected in a receiver 25. From the receiver 25 the liquefied refrigerant passes through a conduit 26 to the cooling unit or evaporator 11. After the refrigerant is expanded in the evaporator 11 by the absorption of heat in the cooling compartment the vaporized refrigerant returns through conduit 27 to the compressor 14 after which the cycle is continued.

The fan 18 draws cooling air through the inlet 19 into the machinery compartment 12 and through the air cooled condenser 17. After passing through the fan 18 the air is circulated across the compressor 14 and motor 15 and is

discharged at 28 through the open rear side of the machinery compartment. Because the fin type condenser 17 presents a relatively flat face having a large number of small openings made 5 up of closely spaced radiating fins any dirt or other foreign matter contained in the cooling air entering the machinery compartment 12 will collect on this face of the condenser 17. In this way the condenser 17 acts as a strainer for dust 10 and other particles entering the machinery compartment and to some extent prevents such matter from being deposited on the other apparatus in the compartment. The front surface of the condenser 17 is easily accessible for 15 cleaning purposes through the removable panel 23, as pointed out above. Hence, it is clear that the operator may remove the panel 23 and clean the face of the condenser 17 with an ordinary cleaning brush or the like, thus removing 20 in one operation, practically all of the dirt and other material which may have been carried into the machinery compartment 12 by the cooling air circulating therethrough. Also the condenser can be conveniently maintained in 25 efficient condition by the removal of such foreign matter from its surfaces. Although the air inlet 19 is located in the base of the machinery compartment 12, the mop-board 21 effectually prevents the deposit of dirt beneath the refrigerator cabinet. As will be seen from the drawing, 30 the removable panel 23 is imperforate and the front and side walls of the refrigerator thus present smooth surfaces which may be easily cleaned by wiping them with a damp cloth or 35 the like.

While I have shown a particular embodiment of my invention in connection with a compression refrigerating machine, I do not desire my invention to be limited to the particular construction shown and described, and I intend in 40 the appended claims to cover all modifications within the spirit and scope of my invention.

What I claim as new and desire to secure by Letters Patent of the United States is:

45 1. A refrigerator cabinet having a cooling compartment and a machinery compartment

therebeneath, a mop-board surrounding the base of said refrigerator and having an offset portion in the front thereof, an air-cooled condenser and a motor and compressor unit mounted in said machinery compartment, an air inlet in 5 the floor of said machinery compartment in front of said offset portion of said mop-board, an air outlet in the rear portion of said machinery compartment, and means for drawing cooling air from said inlet through said condenser and 10 over said compressor unit in series and discharging the same through said outlet.

2. A refrigerator cabinet having a cooling compartment and a machinery compartment therein beneath said cooling compartment, a 15 base for said refrigerator cabinet having an imperforate mop-board extending entirely about the front and sides thereof and closing a space between the bottom of said machinery compartment and the surface on which said base is supported, and a recess in a wall of said base providing a passage for admitting cooling air to an 20 inlet in said machinery compartment.

3. A refrigerator cabinet having a cooling compartment and a machinery compartment 25 therebeneath provided with an opening in the front wall thereof, a mop-board surrounding the base of said refrigerator and having an offset portion in the front thereof, a removable imperforate panel covering said opening, a vertical air-cooled condenser of the fin type mounted in said machinery compartment in parallel spaced relationship with said opening 30 the face of said condenser being accessible through said opening for cleaning purposes, a 35 motor-driven compressor unit supported in the rear of said condenser, an air inlet in the floor of said machinery compartment in front of said offset portion of the mop-board, an air outlet in the rear wall of said machinery compartment, 40 and a fan mounted between said condenser and compressor unit for circulating air from said inlet through said condenser and over said compressor unit in series and discharging the same 45 through said outlet.

RALPH E. KING,
